UNITED STATES PATENT OFFICE.

AUGUST AHLBRECHT, OF PITTSBURGH, PENNSYLVANIA.

AEROPLANE.

1,092,888.

Specification of Letters Patent. Patented Apr. 14, 1914.

Application filed April 17, 1913. Serial No. 761,683.

To all whom it may concern:

Be it known that I, AUGUST AHLBRECHT, a citizen of the United States, residing at Pittsburgh, in the county of Allegheny and State of Pennsylvania, have invented a certain new and useful Improvement in Aeroplanes, of which improvement the following is a specification.

My invention relates to improvements in aeroplanes, particularly bi-planes, and has for its principal object, to provide means therefor to automatically reestablish the balance thereof, transversely, when disturbed by air currents acting on either side thereof.

Other objects are, to provide a rudder construction therefor that is automatic in its movement with that of the plane to establish a longitudinal balance thereof, and which is also arranged for manual operation.

With the above objects in view, the invention consists in certain features of construction, in certain parts, and in certain combinations of parts, as pointed out in the appended claims of this specification.

An embodiment of the invention is illustrated in the accompanying drawings forming a part of the specification descriptive thereof, wherein certain detail parts are given certain numerals and referred to by such throughout the description, said drawings representing the following views:

Figure 1 is a plan of an aeroplane embodying the features of invention. Fig. 2 is a front elevation thereof. Fig. 3 is a side elevation of the same, in section. Fig. 4 is a perspective of a detail part of the same.

The aeroplane structure here shown to illustrate the application of my invention thereto, comprises, briefly, a suitable frame 1, provided with a rearwardly extended portion 2 suitably covered, to which frame is suitably secured an upper and lower supporting plane 3 and 4, respectively, said frame being strengthened by suitably arranged guy-wires 5 and to either the upper plane or frame portion is fixedly attached a platform 6. My improved balance as applied thereto, comprises a plurality of suitably constructed transversely-disposed balancing planes 7, secured in any desired manner to the frame, preferably in such manner as to permit their adjustment vertically or otherwise, by such means, for example, as

the slidable sleeves 7', all of said planes being disposed at an inclination, approximating 30 degrees, transversely to the direction of flight, the planes at one side being inclined in a reverse direction to those at the opposite side, in which position they are maintained, and disposed one above the other. In applying these balancing planes to the aeroplane, it is important that they be positioned at a point beyond the supporting planes thereof, such as shown, leaving an open space above and below the same, so as to not interfere with the proper action of the air currents above and below the same.

If an aeroplane provided with the above described balancing planes should be encountered by an air current flowing toward one side thereof, as for example, at the left side, then said air current acts upon the under side of the balancing planes thereat and raises that side of the aeroplane, causing said aeroplane to dip and tend to descend to the right, the pressure of the sustaining air layer on the right side acting on the underside of the balancing planes thereat, causes the aeroplane to slide or skid upon the air layer until the aeroplane again becomes righted to its normal horizontal position.

My improved steering rudder and operating means therefor, comprises a plurality of horizontally disposed rudder blades 8, hingedly connected at their rear to the frame 1, the forward ends of which are adjustably connected by a rod 9'. A cord or wire 10 is attached to the upper rudder, 90 passing over the pulleys 11 and 12, down and engaging with the pulleys 40, 40', 43, 43' and beneath the pulley 15, thence along to and connecting the vertically disposed and pivoted lever 19 at the lower end thereof, about the pulley 16, up and over the pulley 17, then over the pulley 18, down to and engaging the pulleys 41, 41', 42 and 42', thence about the pulley 14 to and about the pulley 13 to and connecting with the lower rudder, said pulleys being all suitably arranged or connected to the aeroplane.

The manual adjusting means for the rudder blades, comprise a hand lever 20 suitably mounted upon its pivot 20' to the structure and a T-shaped lever 21, also suitably mounted upon its pivot 21' to the structure, said T-lever being provided with spaced

pulleys 22 and 23 for engaging said cord or wire 10, normally forcing it out of alignment between the pulleys 41 and 41' and 40 and 40', both of said levers being connected 5 to one another by paralleling wires 24 and 25. To adjust the rudders manually, the operator adjusts the hand lever 20 upon its pivot, as for instance to the left, to elevate the aeroplane, moving the T-lever 21 in the 10 same direction and causing the pulley 22 thereof to forcibly engage the cord or wire 10, at that side and further depressing it out of alignment and allowing it to align between the pulleys 40 and 40', thus displacing 15 said cord or wire to such extent as to cause it to be moved upon its pulleys and lower the rudder blades from their normal positions, shown by full lines in Fig. 3 to that shown in the same figure by dotted lines, to a 20 greater or less degree, as may be required. The means for automatically adjusting the rudder, comprises a swinging member, preferably a platform 26 adapted for carrying passengers or freight, suspended 25 by rods 26' from a transversely disposed shaft 27 suspended from the underside of the fixed platform, said swinging platform having an opening 28 therein through which the lever 19 extends. 30 said platform 26 being connected to one end of a lever 29, carrying a pulley 30 at its opposite end and pivotally secured to the aeroplane frame, by a wire or cord passing over pulleys 32 and 33 also suitably mounted to 35 said frame. A T-shaped lever 34, provided at its lower end with spaced pulleys 35 and 36, is pivotally mounted to the frame and connected at its upper end with a fixed support, such as the shaft 27, by a wire or cord 40 37. Normally, the lever 29 displaces the wire or cord 37, as does also the pulley 36 of the T-lever 34 displace the wire or cord 10 out of alignment, as shown in Fig. 3, and should the aeroplane be caused to dip 45 downward, for example, the lever 19 will be adjusted by the swinging platform and cause the cord or wire 10 to be moved and adjust the rudder blades to a position such as shown by the dotted lines in Fig. 3, and 50 at the same time the platform will cause the lever 29 to be adjusted and disengage the pulley 30 thereof from the connecting wire or cord 37, thus causing the T lever 34 to be 55 adjusted and the pulley 35 thereof displace the wire or cord 10, at that side sufficient to move said wire longitudinally and cause the rudder blades to be adjusted to about that shown by the dotted lines in Fig. 3. Should the aeroplane dip at its rear, the adjustment

of the rudder blades will be in an opposite 60 direction, as will be apparent.

Having thus shown and described an embodiment of my invention, what I claim and desire to secure by Letters Patent, is:

1. In an aeroplane, the combination of a 65 rigidly-fixed transversely-disposed balancing plane at and projecting beyond each side of the supporting plane, the plane at one side being inclined in a direction opposite to that at the other side and both in a direction transversely to the direction of flight, the space directly above and below said balancing planes being entirely open, and said balancing planes adapted to be adjusted vertically 70 at their fixed points. 75

2. In an aeroplane, the combination of a plurality of rigidly-fixed transversely-disposed balancing planes at and projecting beyond each side of the supporting planes, the planes at one side being all inclined in a 80 direction opposite to those at the other side and all disposed in a direction transversely to the direction of flight, the inner edges of all of said balancing planes being lowermost, and the space directly above the up- 85 permost planes being entirely open. 90

3. In an aeroplane, the combination with a fixed support, of an approximately horizontally-disposed rudder hingedly fixed thereto, a wire forming a loop and having 90 said rudder connected thereto, a pivoted member disposed within said loop and adapted to adjust said loop in the direction of its length to move the rudder, and an adjustable hand-operated member connected to 95 and adapted to adjust said loop member. 100

4. In an aeroplane, the combination with a fixed support, of an approximately horizontally-disposed rudder hingedly fixed thereto, a wire forming a loop and having 100 said rudder connected thereto, a pivoted member disposed within said loop and adapted to adjust said loop in the direction of its length to move the rudder, an adjustable hand-operating member connected to 105 and adapted to adjust said loop member, a swinging platform, and means for automatically adjusting said loop to operate the rudder by the swinging movement of said platform. 110

In testimony whereof, I have hereunto signed my name in the presence of two subscribing witnesses.

AUGUST AHLBRECHT.
